FORGE PROVIDING BOTTOM DISCHARGE
MEANS FOR CLINKERS, REFUSE, AND
THE LIKE

Skidmore, Shipley, Muncie, Ind.

Application November 24, 1950, Serial No. 197,414

5 Claims. (Cl. 110—3.5)

1

This invention relates to improvements in forges. It has reference especially to a forge of the type wherein the open fireplace with forced draft for heating is, by a deck structure, supported at height accommodative to smithing.

A cause of considerable inconvenience in the use of forges as same have hitherto been devised is, that the fireplace residue or refuse as clinkers, scale, metallic fragments, slag and ashes cannot be sufficiently removed otherwise than by the laborious and time consuming procedure of digging and gouging to the bottom of the fire bed. Such procedure, accompanied as it is, by a breaking down of the fire bed mass, and a dispersing of the adjacent fuel, results in interruption of the use of the forge, delay and inconvenience in handling the work, and in increase of operational expense.

To provide means whereby the above named disadvantages may be overcome is the object broadly stated, of my invention. The said general object, also certain aims which are devoted to providing features of construction resulting in economy of manufacture, practicability of installation and efficient use, and in dependability, are accomplished by and my invention is contained in the new construction, combination and arrangement of parts described in the following specification and illustrated in the accompanying drawings.

The different parts of the invention are identified by suitable characters of reference applied to them in the several views in the drawings.

In the drawings

Fig. 1 is a top plan view of my invention and which said invention may be designated as a device to facilitate maintenance of uniformity of fire mass in a forge.

Fig. 2 is an elevational side view of said device, taken in the direction of arrow 2 in Fig. 1.

Fig. 3 is an elevational front view, in the direction of arrow 3 in Figure 2.

Fig. 4 is an enlarged vertical cross section view taken on broken line 4—4 in the direction of arrow 4 in Fig. 2.

Fig. 5 is an enlarged vertical central sectional view taken on broken line 5—5 in the direction of arrow 5 in Fig. 1.

Fig. 6 is a vertical cross section view taken on the broken line 6—6 in the direction of arrow 6 in Fig. 5.

Fig. 7 is a sectional top plan view taken on broken line 7—7 in the direction of arrow 7 in Fig. 5.

Fig. 8 is a sectional top plan view taken on

2

the broken line 8—8 in the direction of arrow 8 in Fig. 5.

Fig. 9 is a sectional top plan view taken on broken line 9—9 in the direction of arrow 9 in Fig. 5.

Fig. 10 is a sectional top plan view taken on the broken line 10, in the direction of arrow 10 in Fig. 5.

Fig. 11 is a diagrammatic front view showing the device as it appears installed.

Fig. 12 is a fragmentary top plan view in the direction of arrow 12 in Fig. 11.

Metal fire pot as of cast iron, has convergent side walls embodying flanges 21 and 22, and convergent end walls embodying flanges 23 and 24. The bottom is provided with rectangular opening 25. Secured to said bottom at position closely adjacent to and in parallel alignment with transverse forward edge 26 of said opening, and spaced as indicated in the drawing (see Figures 1 and 6) are downwardly protruded prongs 28. In providing the opposed flanges 21 and 22 at a level different from the level of the opposed flanges 23 and 24 the pot is rendered adaptable to being readily positioned upon support members conveniently arranged and forming a part of a conventional bench structure, as indicated in Figures 11 and 12.

An elongated connector member and which I designate as a header plate 31 (so called because it constitutes an element to which the hollow case presently referred to is joined to the bottom of the fire pot) is provided with a rectangular aperture 32 that is so located near the end of said plate as to register beneath the opening 25 of said fire pot. Closely adjacent to and in parallel alignment with the transverse forward edge 33 of said aperture are holes 34 positioned to register with and to permit the passing therethrough of the said prongs 28 of the fire pot.

The downwardly directed marginal portion of the said header plate forms a border skirt which bounds the space immediately beneath said plate. Said skirt (as shown in Fig. 2 and Fig. 8) embodies vertical ribs 37.

A grate 38 positioned immediately underneath said plate and between the opposed sides 35 and 36 of said boundary skirt, has the predeterminedly spaced longitudinal slots 39. By means of a handle 40 whose stem 41 is passed through a hole provided therefor in the front end wall 42 of said border skirt and is secured to the forward end of said grate, the said grate may be manually operated.

An upright hollow case, open at its upper end,

has side walls 43 and 44, rear wall 45 and frontal wall 46. The lower end of the rear portion of said case is of form in plan to provide enclosed space D, and outlet 47. The space E bounded by the upper part of said case is of length coextensive with the length of the space bounded by the border skirt of the said header plate. The distance between the side walls 43 and 44 of said case being less than the distance between the longitudinal parallel sides 35 and 36 of said skirt, the inner portions of the top flanges 49 of the said side walls of the case, provide parallel opposed seats 50 upon which said seats the aforesaid grate rests slidably at the under faces of its sides.

The frontal wall 46 of said case is inclined downwardly and rearwardly to a plane spaced above, and is then directed downwardly and terminated at the plane of the said outlet 47. In each of the side walls of said case at its lower portion and at a location above the plane of the space D is provided an inlet opening 55. At one of these openings 55 (for example the opening in wall 43) is provided a connector fitting 56 for the reception of pipe (which is indicated at B in Figure 11) through which air is propelled for the forced draft. At the other opening 55 a closure plate 57 is secured as by cap screws 58.

The fitting 56 and the closure plate 57 being interchangeable, the pipe may be connected either at the right hand position, or at the left hand position, as may be desired. A trap door which closes the outlet 47 consists of a plate 60 having ear 61 and a downwardly turned finger hold 62. Said door is pivotally connected at its ear to a stud 63 which is fixed to and projects downwardly from the bottom edge of wall 45 of the case. Said plate is maintained yieldingly in its position as by a coil spring 64 interposed between the ear 61 and a burr 66 secured to the bottom of said stud. A stop lug 68 (see Fig. 2) integral with the side wall at said outlet 47 is engaged by the trap door when it is swung from the open or broken line position (see Figure 10) to closed position.

By means of screws 70 passed through holes provided therefor in the flanges 49 of the case, and in the ribs 37 of the sides of the skirt of the header plate 31; and into threaded holes therefor in the bottom of the fire pot; and by screws 71 passed through holes provided therefor at the frontal end of said head plate; the said fire pot, header plate, and case are bound in united relation. The prongs 28 will have become engaged in the slots of the grate. The fire pot opening and aperture of the header plate will have been brought into registration. The grate resting free upon the seats 50 and above the elongated open space E (see Fig. 5) is movable slidably, the slots thereof being raked by the said prongs 28.

At all times during the use of the fire, the trap door is in the closed position. Flow of the draft is through inlet 55 and upwardly through the grate slots 39, aperture 32 and opening 25 to the fire pot.

When in the course of smithing operations impairment of the fire occurs, and which occurrence is indicatory that accumulation of refuse at the fire mass is impeding the draft, the smith grasps the handle 40. If the refuse accumulation is only relatively slight, a jiggling of the grate may sufficiently loosen the obstruction that it drops through the grate. In the refuse accumulation is dense and the ash content is of depth then the grate is operated its full stroke. In this move-

ment of the grate the sides of the slots, scraping as they do against the prongs, cause a breaking up and dislodgement of said refuse. The space E below the grate being clear and unrestricted throughout the entire distance traversed by the grate, there is no impediment to prevent free escape from the slots and surfaces of the grate, and from the clearance spaces about the grate, of all refuse and sediment there present. Accordingly the grate is at all times readily movable.

The refuse escaping as it does into the zone immediately below the space E comes to rest in the space D and on the trap door. Such portion of the refuse as in the movement of the grate may be carried forwardly, and which escapes into the space between the forward portions of the side walls of the case, slides down on the interior face of the forward wall and is received at the said space D. At such time as may suit the smith during the period that the blast is not in operation, the emptying of the case and release of the refuse collected in the space D at the outlet is accomplished by simply applying a finger to the handle 62 and swinging it to the broken line position indicated in Fig. 10.

Whereas the several parts are shown and described as of form, structure and detail preferred, it will be understood that modifications may be made, within the spirit and scope of the invention as same is defined in the claims, without departing from the principle of my invention or sacrificing any of its advantages.

What I claim as my invention is:

1. Forge equipment comprising a fire pot having an opening in its bottom, prongs downwardly protruded from the bottom of said fire pot disposed in a row transversely across the width of said opening, an elongated header plate secured at an end portion thereof to the bottom of said fire pot there being in said end portion an aperture to register with the opening of the fire pot, and there being holes in a row transversely across the width of said aperture that is proximal the pronged side of the opening of the fire pot and through which said holes the said prongs are passed and beyond which they extend, the edges of said header plate being turned downwardly forming a border skirt having opposed spaced parallel longitudinal portions, a grate positioned beneath said header plate, said grate being longer than the extent of the aperture in said header plate but shorter than the longitudinal space within the border skirt of said header plate, and having longitudinal slots in which the extended portions of the said prongs are engaged, a handle with stem portion extended reciprocably through an opening located in the end wall of the skirt of said header plate and attached to said grate, an upright hollow case open at its upper end and of interior width less than the interior width of said border skirt, to provide spaced longitudinal seats upon which the said grate is supported slidably at the undersides of its longitudinal edge portions, said case being secured at its top edges to the underside of the border skirt of said header plate whereby it communicates with the lower side of said grate and with the space defined by said downwardly directed border skirt, said case in a portion thereof adjacent to the apertured portion of said header plate being provided with an air inlet, and in the bottom portion being provided with an outlet, and a trap door closing said outlet.

2. A device to facilitate maintenance of uniformity of fire mass in a forge, comprising a

fire pot having an opening in its bottom, a prong protruded downwardly from the bottom of said fire pot closely adjacent to a transverse side of said opening, an elongated flat head member embodying downwardly directed border skirt embodying opposed parallel longitudinal sides and transverse ends, there being an aperture in an end portion of said head member to register with the opening in said fire pot, and there being a hole in said head member through which the said prong is passed and beyond which it extends, a grate positioned beneath said head member and between its longitudinal sides, and having a longitudinal slot engaged by said prong, a handle with stem extending from said grate and through an opening in a transverse side of said head member, a hollow case open at its upper end and of interior width less than the distance between the inner faces of the sides of said head member, the top edges of said case forming seats upon which said grate is supported, the said case in a side thereof adjacent to the apertured portion of said head member having an air inlet, and at its bottom portion being provided with an outlet, a trap door for said outlet, and means to secure the fire pot, head member, and said case in united relation.

3. In forge apparatus including a fire pot with an opening in its bottom, and a slotted grate therefor, a fixed member to support the grate at position underneath the fire pot opening and to permit of its being moved reciprocably in the space below said opening, and also to be moved to a position clear of said opening, an operator handle attached to said grate, and there being holes in said fixed support member arranged in a row closely adjacent to a side of the fire pot opening, and prongs downwardly protruded from the bottom of said fire pot in a row from the bottom of said fire pot, across the width of and closely adjacent to a transverse side of said fire pot opening and which are passed through the holes in said fixed member and to engagement within the slots of the grate.

4. In forge apparatus, in combination with a fire pot having an opening in its bottom, an elongated header plate secured at an end portion thereof to the bottom of the fire pot and having an aperture in said end portion in registration with the fire pot opening, and holes in a row across the width of and closely adjacent to a transverse side of said aperture, said header plate embodying downwardly directed border skirt having opposed parallel longitudinal sides and transverse ends, prongs downwardly protruded from the bottom of said fire pot, in a row across the width of and closely adjacent to a transverse side of the opening in said pot, which said prongs are passed through the holes in said header plate and beyond which said holes they extend, a grate positioned at the underside of said header plate, said grate being longer than the extent of said aperture but shorter than the longitudinal space within the border skirt of said header plate, a handle attached to said grate and operable reciprocally through an opening in an end wall of the skirt of the said header plate to move the grate, an upright hollow case open at its upper end and united at said upper end to said header plate, the said case at the portion thereof beneath the aperture of the head plate having an outlet at its bottom and an air inlet in a side wall thereof, the cross wall of the opposite end of the case being inclined downwardly from the plane of the opposite end

10 of the header plate to a point above said outlet in a plane slightly above the plane of the bottom of the case, and a trap door for said outlet.

5. Forge equipment comprising a fire pot rectangular in plan formation, with convergent side walls each embodying a flange at its upper portion, and convergent end walls each embodying a flange at its upper portion, the flanges of the side walls being at a plane above the plane of the flanges of the end walls, the bottom of said pot having a rectangular opening, prongs downwardly protruded from the bottom of said fire pot in a row across the width of, and closely adjacent to the forward transverse side of said opening, an elongated header plate secured at the rear end portion thereof to the bottom of said fire pot, there being in said rear end portion of said header plate a rectangular aperture to register with the rectangular opening of the fire pot, and there being holes in a row adjacent to and across the width of the transverse side of said aperture that is proximal the pronged side of the fire pot opening and through which said holes the said prongs are passed and beyond which said holes they extend, the edges of said header plate being turned downwardly forming a rectangular border skirt embodying spaced parallel longitudinal sides which extend forwardly of said fire pot a predetermined distance, a grate rectangular in plan formation positioned beneath the header plate and having longitudinal slots substantially equivalent in length to that of the aperture of the head plate and within which said slots the extended portions of the said prongs are engaged, said grate being longer than the extent of said aperture but shorter than the longitudinal space within the border skirt of said header plate, a handle with stem attached to the grate and passed through a hole therefor in the forward end of the skirt of the header plate, and manually reciprocable to move the grate, an upright hollow case open at its upper end and embodying side walls, transverse rear wall and transverse forward wall, the lower end of the rear portion of said case being of form in plan to provide an enclosed space and a bottom outlet, the upper end of the case being coextensive with the space defined by the border skirt of the head plate, the distance between the side walls of the case being less than the distance between the longitudinal sides of said skirt the tops of said side walls forming seats upon which said grate rests, the frontal wall of the case being inclined downwardly and rearwardly to a plane spaced above and then directed downwardly and terminated at a plane of the said outlet, there being an air inlet in at least one of the side walls at the rear portion of said case, a trap door closing said outlet, and means to secure the fire pot, header plate, and case in united relation.
